UNITED STATES PATENT OFFICE.

MARCELLUS JACKSON BUNNELL, OF TAYLOR, TEXAS.

HILLSIDE-PLOW.

SPECIFICATION forming part of Letters Patent No. 400,434, dated April 2, 1889.

Application filed November 15, 1888. Serial No. 290,889. (No model.)

To all whom it may concern.

Be it known that I, MARCELLUS JACKSON BUNNELL, a citizen of the United States, residing at Taylor, in the county of Williamson and State of Texas, have invented new and useful Improvements in Hillside-Plows, of which the following is a specification.

This invention relates to improvements in hillside-plows; and it consists in a certain novel construction and combination of devices fully described hereinafter in connection with the accompanying drawings, and specifically pointed out in the appended claims.

In the drawings, Figure 1 is a perspective view of a plow embodying my improvements. Fig. 2 is a rear view of the same. Fig. 3 is a longitudinal sectional view on the line $x-x$ of Fig. 2, looking toward the beam. Fig. 4 is a detail perspective view of the front end of the beam. Fig. 5 is a similar view of the rocking plate to which the tongue is attached.

Referring by letter to the drawings, A designates the main frame of the plow, having the longitudinal beam B, to one side of which near its front end is attached the bracket b, having vertically-aligned eyes b' b' on its outer end, and C designates a vertical shaft mounted in the said eyes and provided with a stationary collar c, which bears against the under side of the lower eye. The lower end of this shaft is bent outward horizontally to form the spindle C' for the front furrow-wheel, C², and the upper end of the said shaft 35 is bent inward to form a horizontal spindle, C³.

The rocking plate D is provided on its under side with the depending apertured ears d d which are mounted on the spindle C³, and the rear end of the tongue E is attached to the said plate, and is therefore capable of vertical movement at its free end. The rocking plate is provided near its front edge with a series of perforations, d' d', in one of which a bolt, e, which extends through the tongue near its rear end, is engaged, and the said plate is further provided at its rear edge with a series of transverse slots, d² d², corresponding in number to the perforations d' d' and adapted to be engaged by a vertical bolt, e', 50 which passes through the rear end of the tongue. The tongue is thereby allowed a slight lateral movement at its free end.

The rigid plow-standard F depends from the beam near its rear end, and is provided with a rearwardly-extending arm, f, having a vertical eye, f', at its rear end, and G represents a downwardly-inclined spindle, provided with a vertical extension, g, which is mounted in the said eye f'. A brace-bar, H, is attached at its upper end to the rear bar, a, of the plow-frame, and is provided at its lower end with an eye, h, through which passes the upper threaded end of the extension g, and the said extension is engaged above the eye h by a nut, g². The rear furrow-wheel, G', 65 which is mounted on the inclined spindle G, is designed to run in the "live" furrow, while the front furrow-wheel runs in the preceding or old furrow.

K designates a movable arm pivoted near its lower end to the extremity of the standard and provided with a curved plate, k, to which the plowshare L and the mold-board L' are attached. A brace-bar, M, extends from the upper end of the mold-board to the movable arm, and is provided at a suitable point with a loop, m, which receives and operates on the standard F, and thereby steadies the movable arm.

To a curved bracket, N, which is arranged on the upper side of the beam, is pivoted the operating-lever O, having a toothed sector, o, on its lower end, which meshes with the toothed T-head on the upper end of the movable arm K, so that when the said lever is moved forward or backward by the operator the point of the plowshare is respectively elevated or depressed, for the purpose which will be readily understood.

The standard F is extended a short distance above the beam B, and to its upper end is attached a curved rack, f², which is engaged by a spring-actuated latch, P, on the operating-handle to lock the latter in the desired position.

Q represents a transverse shaft mounted on the frame of the plow and provided at one end with a crank-arm, q, having a spindle, q', on its free end, on which is mounted the wheel Q', and the operating-handle R, which is attached to the said crank-arm, extends up within reach of the operator, and is provided with a spring-latch, r, to engage a rack, R', on the frame of the plow.

A swinging link, S, is mounted on a transverse bolt, s, in the bifurcated front end of the beam, the said link being horizontally slotted at its front end, and T represents a curved bar, which is provided with a series of perforations, t t, adapted to be engaged by a vertical bolt, t', in the front end of the link. A connecting-rod, U, is attached at its front end to one end of the curved bar, and at its rear end to an eye, u, on the side of the beam. The curved bar is therefore capable of transverse adjustment on the plow-beam, and is also capable of vertical movement.

Having thus described the invention, I claim—

- 15 1. In a plow, the combination of the standard depending from the frame of the plow, the movable arm pivoted to the said standard near its lower end and having the plow-share fixed thereto, and the operating-lever mounted on the plow-frame and provided with a toothed sector meshing with a toothed T-head on the upper end of the said movable arm, substantially as specified.
- 20 2. In a plow, the combination, with a standard depending from the frame thereof, of the movable arm pivoted near its lower end and having the plowshare and mold-board affixed thereto, the operating-arm mounted on the

30 said frame and provided with a toothed sector meshing with a toothed T-head on the upper end of the movable arm, and the brace-bar extending from the mold-board to the movable arm and provided at an intermediate point with a loop, m, operating on the 35 standard, substantially as specified.

3. In a plow, the combination, with the beam, of the depending standard, the movable arm pivoted to the standard near its lower end, and provided at its lower end with a 40 curved plate, k, and at its upper end with a toothed T-head, the plowshare secured to the said curved plate, the operating-lever mounted on a bracket arranged on the said beam and having a toothed sector meshing with 45 the toothed T-head, and the spring-actuated latch mounted on the lever and engaging a toothed rack on the upper extended end of the standard to lock the lever in the desired position, substantially as specified. 50

In testimony that I claim the foregoing as my own I have hereto affixed my signature in presence of two witnesses.

MARCELLUS JACKSON BUNNELL.
